United States Patent Office.

AUSTIN Z. MASON, OF ADRIAN, MICHIGAN, ASSIGNOR TO HIMSELF AND
RICHARD B. ROBBINS, OF SAME PLACE.

Letters Patent No. 77,390, dated April 28, 1868.

IMPROVEMENT IN VISE.

The Schedule referred to in these Letters Patent and making part of the same.

TO ALL WHOM IT MAY CONCERN:

Be it known that I, AUSTIN Z. MASON, of Adrian, in the county of Lenawee, and State of Michigan, have invented a new and useful Improvement in Bevel-Vise Jaws; and I do hereby declare that the following is a full, clear, and exact description of the construction and operation of the same, which will enable others skilled in the art to make and use my invention, reference being had to the annexed drawings, and to the letters of reference marked thereon, making a part of this specification, like letters referring to like parts.

In the drawings—

Figure 1 represents a perspective view of a bevel-vise jaw embodying my invention.

Figure 2 represents a vertical section.

Figure 3 represents a perspective view of the three several parts of my improved bevel-vise jaw, when slightly separated.

A represents the movable jaw.

F represents the stationary jaw.

B represents a washer-plate, attached to the movable jaw A.

C represents an adjustable ring.

This ring has, on its back side, a short hub, *t*, (fig. 3,) to fit into the opening in the washer-plate B, and on the other side the ring C is formed by two equally-inclined planes, *x* and *y*, whose obliquity to the plane of the back side of the ring is equal to the greatest possible bevel which the jaw is designed to clasp.

The opening through the centre of the ring is concave, corresponding to the semispherical bilge D on the face-plate D'. By means of a handle, *h*, the ring may be readily turned around a quarter circumference, thus causing the face-plate D' to rock either way down upon the inclined planes *x* and *y*, thus giving any desired angle to the face-plate D'.

To the face-plate D' is attached, if desirable, a wooden disk, E, to intervene between the face-plate D' and the wedged-shaped piece W to be clamped.

In order to clamp the bevelled or wedge-shaped piece W inverted, you have only to unscrew the screw S, take out the wedge, and turn the edge, nearest you, of the face-plate D' back against the inclined plane *x* of the adjustable ring C, invert the wedge, and place it back in the vise, and turn up the screw.

If you wish to place the wedge in the vise in an oblique position, with the thick end either up or down, you have only to turn the handle, *h*, of the adjustable ring, C, up until the line of intersection of the two planes *x* and *y* shall reach a horizontal position, when the wedge can be readily clamped as before, in the manner desired.

A bolt, P, holds the face-plate D' and adjustable ring C in working position with the movable jaw A, and the two prongs *m* and *n*, and projection *o* of the face-plate D', prevent the latter from a rotary motion around the bolt P.

Having thus described my invention, what I claim as new, and desire to secure by Letters Patent, is—

1. I claim the adjustable ring C, constructed with oblique faces *x* *y*, and a handle, *h*, for turning it on its axis, to adapt it to impart any desired set to the face-plate D', in the manner and for the purposes set forth.

2. I claim, in combination with the adjustable ring C, the washer-plate B, and the face-plate D', with its spherical bilge D, all constructed in the manner set forth and described.

AUSTIN Z. MASON.
